United States Patent Office.

JEARUM ATKINS, OF MOKENA, ILLINOIS.

Letters Patent No. 74,034, dated February 4, 1868.

IMPROVEMENT IN GATES.

The Schedule referred to in these Letters Patent and making part of the same.

TO WHOM IT MAY CONCERN:

Be it known that I, JEARUM ATKINS, of Mokena, Will county, in the State of Illinois, have made new and useful Improvements in Farm-Gates; and I hereby declare the following to be a full and exact description of the same, reference being had to the drawings that accompany and form a part of these specifications.

My invention consists in operating a gate upon parallel levers in such a manner that it moves horizontally in rectilinear lines, and with the least possible resistance or friction in being opened or closed.

Figure 1 is an elevation.

Figure 2, a bird's-eye or top view.

Figure 3, a cross-section, taken on a line *b c*, seen in fig. 1.

Letters A A, two posts connected at their upper ends by means of the cap or cross-piece B. The gate consists of the perpendicular end-pieces N and slats *p p*, and the horizontal or guiding-bar G, and is suspended between the posts A A by means of the radius-bar R and the braces S S. There are two extra slats, *t u*, opposite the upper and second slat from the bottom of the gate. The radius-bar R passes between the slats *p t* at the top, its lower end extending between the slats *p u*, to which it is secured by a pin, *i*. The braces S S, which are half the length of the bar R, are secured to the centre of the radius-bar by the pin *k*, and to the posts A A by the pin *l*. The radius-bar is jointed at its upper end to the parallel bar D, said bar being jointed at its opposite end to the post E. The position of the radius-bar R and the braces S S, when the gate is open, is shown by the dotted lines in fig. 1. The horizontal bar G, which extends on a line with the upper slats back to the post E, works through a mortise in said post, for the purpose of guiding the gate in its movements horizontally, keeping it from being blown or swinging either one way or the other. A friction-roller, F, is placed in the mortise, under the bar G.

Another mode for guiding the upper end of the radius-bar in its up and down movements, as the gate opens and closes, is represented in dotted lines shown at *n* in fig. 1. It consists in placing two rollers upon the pin that passes through the radius-bar, said roller to work in grooves in the posts A A. By adopting this last-described arrangement the parallel bar D may be dispensed with, and the post E, in that case, need be only high enough to guide the horizontal bar G. By proportioning all the parts as described, it will be seen that the gate will have a perfectly horizontal rectilinear movement in opening and closing; the weight of the bar R being sufficient to hold the gate when closed without any other fastening, and when open holds it in that position. In opening or closing the gate, after it has passed the centre, it moves of its own accord, the post E serving as a stop to limit the motion of the gate on opening, and the post C serving the same purpose when closing.

What I claim, and desire to secure by Letters Patent, is—

A gate, constructed as described, having the pivoted braces R S, post A, and guide-bars D G, and post E, all arranged and operating as specified.

In testimony whereof, I have signed my name to this specification in the presence of two subscribing witnesses.

JEARUM ATKINS.
